INVENTOR:

Friedrich Brune.

UNITED STATES PATENT OFFICE.

FRIEDRICH BRUNE, OF ELIZABETH, NEW JERSEY.

WIRE-BENDING TOOL.

SPECIFICATION forming part of Letters Patent No. 394,331, dated December 11, 1888.

Application filed October 18, 1888. Serial No. 288,513. (No model.)

To all whom it may concern:

Be it known that I, FRIEDRICH BRUNE, a subject of the Emperor of Germany, and at present residing in Elizabeth, in the county 5 of Union and State of New Jersey, have invented a new and Improved Wire-Bending Tool, of which the following is a full, clear, and exact description.

The invention relates to a tool specially 10 adapted for bending the wire on bottle-stoppers, such as shown and described in the Patent No. 158,406, dated January 5, 1875, and granted to Charles de Quillfeldt, of New York city.

15 The object of the invention is to provide a new and improved tool which is very simple and durable in construction, effective in operation, and serving to quickly and accurately bend the supporting wire or yoke of the stopper, so as to refit the latter onto the mouth of the bottle.

20 The invention consists of various parts and details and combinations of the same, as hereinafter more fully described, and pointed out 25 in the claims.

Reference is to be had to the accompanying drawings, forming part of this specification, in which similar letters of reference indicate corresponding parts in all the figures.

30 Figure 1 is a side elevation of the tool as applied to a bottle-yoke. Fig. 2 is a plan view of the same. Fig. 3 is a transverse sectional elevation of the same on the lines *xx* of Fig. 1, and Fig. 4 is a like view of part of the same in 35 a different position.

The improved wire-bending tool A is provided with the two members B and C, hinged together at one end at D, and having their other ends formed into the handles E and F, 40 respectively.

The member B is provided between the pivot D and the handle E with the straight flat part G, having on its under side the downwardly-extending lug H. The said flat part G and 45 its lug H are adapted to pass between the forked part I of the member C, which latter thus forms a guide for the member B.

The forked part I is straight and continuous with the downwardly-extending short arm 50 J, on which the rearwardly-projecting handle F is formed. From the lower end of the arm J projects forward and parallel with the forked

part I the arm K, having in its top a recess, L, into the middle of which is adapted to pass the lug H when the handles E and F are 55 pressed together. From each side of the arm J extends a downwardly and forwardly inclined L-shaped finger or prong, N.

When bottle-stoppers such as described in the patent above mentioned are used for some 60 time, the stopper does not fit snugly on its seat on the bottle on account of wear or other causes, thereby permitting leakage of the bottle when the stopper is seated. Now in order to again fit the stopper snugly on the bottle 65 I employ the tool above described and proceed as follows: When the bottle is open, the stopper O is moved to one side of the supporting wire or yoke P, as is plainly shown in Figs. 1 and 2, and the wire P is preferably 70 placed in a vertical position. The operator now takes hold with one hand of the handles E and F and opens the members B and C, so that the bottom of the lug H is above the top of the arm K. The latter is now pushed under the middle part of the wire P, so that the 75 said middle part rests across the top of the arm K. The prongs N by this movement pass over the sides of the wire P, thereby holding the latter firmly in place. The operator 80 presses the handles E and F toward each other, so that the lug H moves downward onto the top of the middle part of the wire P, which part rests over the recess L on the arm K. A further pressing of the handles E and 85 F causes the lug H to bend the middle part of the wire P downward into the recess L of the arm K, as plainly illustrated in Fig. 4. The tool A is then removed from the bottle-stopper and the stopper O is hung into the 90 bend on the middle part of the wire P. The stopper O now hangs considerably lower, as before, on the wire P, and when the stopper is moved above the mouth of the bottle and then pressed downward in the usual manner 95 it fits snugly onto its seat on the bottle.

It will thus be seen that by this simple tool I am enabled to refit the stopper very quickly and accurately on the bottle.

Having thus described my invention, I 100 claim as new and desire to secure by Letters Patent—

1. A wire-bending tool comprising two members hinged together at one end and of which

one member is forked, an arm having in its top a recess and formed on the said forked member, and a lug formed on the other member directly above the said recessed arm and passing through the said forked member, substantially as herein shown and described.

2. A wire-bending tool comprising two members hinged together, a lug formed on one of the said members, an arm formed on the other

member and having a curved recess in its top 10 directly below the said lug, and prongs projecting from the sides of one of the members and extending downwardly and forwardly, substantially as described.

FRIEDRICH BRUNE.
